UNITED STATES PATENT OFFICE.

HARRY A. STERN, OF NEW YORK, N. Y.

CIGARETTE AND CIGAR CONTAINER.

1,187,198.

Specification of Letters Patent. Patented June 13, 1916.

Application filed July 12, 1915. Serial No. 39,213.

To all whom it may concern:

Be it known that I, HARRY A. STERN, a citizen of the United States, residing at New York, in the county of New York and State 5 of New York, have invented a new and useful Cigarette and Cigar Container, of which the following is a specification.

This invention relates to packages or containers for holding cigars, cigarettes, 10 matches or other articles, and its object is to provide a container which shall be strong and durable, and which can be opened without injury to the contents and thereafter closed and again opened as may be desired 15 without affecting the contents.

This invention consists in a proper blank folded in such a manner as to constitute a rectangular receptacle for the articles to be retained, a flap which may be folded down 20 over the opening in the receptacle, and reinforcing covers which may be folded over from the sides to constitute further protection. Sealing means for the contents of the 25 container may be provided if desired.

25 The invention may be embodied in a number of different forms, of which four are shown, but it is to be understood that I am not to be limited to the constructions shown in the drawings, as these are merely examples of the embodiments of the invention.

In the accompanying drawings, Figure 1 30 is a plan of a blank of paper or other flexible fibrous material adapted to be folded to constitute the container. Fig. 2 is a plan of 35 the container after the lower section has been folded up onto the middle section, and the pocket thereby formed has been filled with cigarettes. Fig. 3 is a section of the 40 container on the line 3—3 of Fig. 2 on a larger scale. Fig. 4 is a plan of the container completely closed and sealed. Fig. 45 5 is a plan of a modified form of blank.

Similar reference characters refer to like parts throughout the several views.

45 Containers for cigarettes now on the market are almost universally in the form of comparatively rigid boxes, or of round cylinders of paper or tinfoil, whose ends are folded down onto the contents and usually 50 reinforced by means of a cylindrical band of greater or less stiffness. After these cylindrical containers are filled they are usually flattened to more nearly adapt them to the pocket of the consumer.

55 The present invention is designed to provide a container in which the cigarettes will

be in a single flat row, completely protected from injury, and which container shall be sufficiently flexible so as not to be inconvenient to the person carrying it in any 60 of his pockets.

It will be understood that the material from which the various containers shown in the drawings are to be made is paper, properly sized and stiffened cloth, leather, properly treated rubber or other flexible material, but preferably a moderately stiff and quite tough paper. It will be further understood that advertisements of any character 65 may be printed on the blank before it is folded to form the container and that the material used may be so treated as to render it moisture proof, and that the parts may be secured together by cement or glue, by sewing, by metal fasteners or in any other desired manner.

The blank shown in Fig. 1 consists of a central portion 1 and side portions 2 and 3 which constitute the middle section of the blank, a central portion 4 and side portions 5 and 6 which constitute the lower section of the blank, and a central portion 7 and side portions 8 and 9 which constitute the upper section of the blank. To form the 70 pocket in which the cigarettes are to be placed, the lower section is folded up against the middle section, the portions 5 and 6 lying against the portions 2 and 3, respectively. If desired, the edges of the portions 75 5 and 6 may be coated with glue or any other proper cement, previous to the lower section being folded over, or any other means may be adapted to secure these portions together. It will then be understood that a 80 pocket of proper size to hold the desired 85 number of cigarettes A is formed of the portions 1 and 4, as shown in Fig. 2, the portion 4 being preferably of less height than the portion 1, although this is a matter 90 of choice. After the pocket has been filled, the upper section is folded down onto the middle section, the portion 7 completely covering the upper ends of the cigarettes A, 95 after which the sides, which are now constituted by the portions 2, 5 and 8, and the portions 3, 6 and 9, respectively, are folded over inwardly, as shown in Fig. 4, after which a seal 11, which may be a revenue stamp or any other form of sticker, may be pasted across the overlapping edges of the 100 portions 2 and 3.

It will be seen that the two sides or flaps

are formed of at least two full thicknesses and in addition thereto the portions 8 and 9, and that these sides are of the full length of the cigarettes. Furthermore, the entire thickness of the package is merely that of the cigarettes plus possibly eight thicknesses of paper. Because of the cement used to secure the parts 2 and 5 and the parts 3 and 6 together, the side portions of the package, after these parts have been cemented, become sufficiently stiff to offer considerable resistance to breakage of the contents through the bending of the package. All the edges of the package when filled are round, and the package yields readily to fit in any vest pocket.

If desired, a leaf 12 of tinfoil or other suitable material may be secured to the upper and middle sections of the blank, as indicated in Fig. 1, so that when the upper section is folded down over the cigarette A, this piece of tinfoil will inclose the exposed ends of the cigarettes and thus prevent the tobacco therein from drying out. It will of course be understood that any other desired means may be employed to prevent the tobacco from drying out; many of these being on the market at present and forming no part of my invention.

In the event that a slightly more rigid container is desired, additional portions 15 and 16 may be formed on the blank, being united to the portions 2 and 3, as shown in Fig. 5. These are folded over onto the portions 5 and 6 respectively, after the lower section has been folded up as previously described, the result being an additional thickness of material in each one of the sides of the package. The pocket formed by folding up the lower section will be of the same character as that previously described, and the entire construction, will have the same appearance as that shown in Fig. 4.

While the description thus far has designated cigarettes in all cases, it will be apparent that whether the containers are to be used for cigars, cigarettes or matches will not affect anything but the size, and that the size and proportions may be changed to suit these containers to articles of practically any size without departing from the spirit of my invention as set forth in the claims. It will also be understood that parts which may be considered unnecessary may be omitted. These containers can be produced at very low cost, especially as the folds are always in the same direction. They are substantially moisture and dust proof and so thin that they do not bulge the pockets. Each cigar or cigarette can be removed without disturbing the others, especially as

all are in plain sight for the distance that they project above the edges of the pockets. Because of their cheapness, they will be adapted to the packaging of a smaller number of cigarettes than is at present possible, especially for use at banquets and for advertising samples.

I claim:

1. A container formed of a blank of fibrous material and consisting of three sections, each section being formed of three portions, the lower section being folded up against the middle section, the inner portions of the middle and lower portions forming a pocket and the outer portions of the lower and middle portions being cemented together to constitute sides, the upper section being folded down over the middle and lower sections after which the sides are folded in over the upper section and the opening to said pocket, said sides and upper section being foldable away from the opening of said pocket to permit the contents thereof to be removed.

2. A container formed of a blank or fibrous material and consisting of upper, middle and lower sections, the middle and lower sections being formed of three portions, the lower section being folded up against the middle section, the inner portions of the two sections forming a pocket and the outer portions of the two sections being cemented together to form sides, the upper section being folded down over said pocket after which the sides are folded in onto the upper section and said pocket.

3. A container formed of a blank or fibrous material consisting of upper, middle and lower sections, the lower section being folded up against the middle section and cemented thereto along their lateral edges so as to form a pocket and a side flap, and the upper section being folded down over the opening to said pocket, after which the side flap is folded in over the upper section and the pocket to protect the contents thereof.

4. A container formed of a blank of paper consisting of upper, middle and lower sections, the lower section being folded up against the middle section and cemented thereto so as to form a pocket and a side flap, a leaf of metal foil secured to the blank along the back of the pocket and the upper section so that when the upper section is folded down the metal foil will close the opening of the pocket, after which the flap is folded down onto the upper section and said pocket.

In testimony whereof I sign this specification.

HARRY A. STERN.
